Specification of Letters Patent.

Patented June 7, 1921.

Application filed December 22, 1920. Serial No. 432,395.

To all whom it may concern:

Be it known that we, ALVAH P. THOMPSON and WILLIAM L. BAXTER, citizens of the United States of America, and residents of Salem and Beverly, respectively, in the county of Essex and State of Massachusetts, have invented new and useful Improvements in Clips, of which the following is a specification.

10 This invention relates to clips and more particularly to clips peculiarly adapted for use in stretching skins, hides and the like upon a drying frame.

15 The most efficient drying apparatus for this purpose consists essentially of a metal frame provided with a sheet of wire mesh or other foraminated or reticulated material yieldingly stretched thereon, upon which the hide or skin is supported and held during 20 the drying operation by clips adapted to grip the skin at the edge portion thereof and having hooks or spurs which hook into the openings in the foraminated support.

25 Broadly speaking the principal object of this invention is to provide a clip of this general type of simplified and durable construction thus facilitating ease of manipulation in service as well as economy in the cost of manufacture and consequently permitting sales at a relatively low price. A 30 more specific object of the invention is to provide a clip wherein the actuating member and the mount therefor, upon which the principal wear comes in service, are formed 35 independent of the body of the clip and can thus be made of a material or grade of material peculiarly adapted to withstand the wear of service without material increase in cost of the device as a whole, such construction also eliminating the weakness resultant 40 upon bending or folding the material of the clip to provide a mount for the actuating member.

45 In the accompanying drawings, Figure 1 is a side view of one embodiment of the invention, the clip being shown in closed position;

Fig. 2 is a side elevation viewed from the left of Fig. 1;

Fig. 3 is a side elevation viewed from the right of Fig. 1;

Fig. 4 is a central longitudinal section of the clip shown in Fig. 1;

Fig. 5 is a view similar to Fig. 4, but showing the clip in open position; and

Fig. 6 is a section on the line 6—6 of Fig. 4.

The clip comprises a band 1 of steel or other suitable flexible material bent so as to bring the ends into juxtaposition to provide material gripping jaws 3 and 4 and an enlarged aperture 2 of suitable size to form a finger opening by which the clip may be grasped and manipulated. The extremities of the jaws are shaped or bent to form 65 complementary interfitting members adapted when forced together firmly to grip the hide or skin at an edge portion thereof. The interfitting jaw members may be of varying construction but we prefer the form shown 70 wherein the jaw 3 is formed with a recess or socket 3^a into which the free end of the jaw 4 fits.

Each of said jaws is provided near its material gripping end with a pair of parallel, 75 spaced slots 5, (Fig. 6) in which is loosely disposed a U-shaped bow 6 of steel or other suitable material forming a mount for the jaw actuating member or arm 7. The free ends of said bow or mount extend through and 80 project beyond one of the jaws as 3 and the actuating member, which has an inner end 8 projecting at substantially a right angle from the outer end of the arm, is pivoted to the projecting portions of said bow in any 85 suitable manner as by trunnions 9 carried by said actuating member and extending into openings provided for that purpose in the free ends of said bow.

The organization and arrangement of the 90 parts above described is such that when the arm 7 is swung toward the body of the clip its inwardly extending end 8 engages the adjacent jaw 3 and forces it inward into the closed or stock gripping position shown in 95 the drawings.

Near the upper or finger engaging portion of the clip and upon the opposite side

from said jaw actuating member 7, there is provided a spur or hook 10. Said spur or hook which faces toward the jaws of the clip and is preferably struck up from the band 1, is adapted to be hooked into the sheet of wire mesh or other foraminated stock support of the drying frame. In use the clip should lie flat or substantially flat upon the stock support and therefore the material between the slots 5 in the jaw 4 is preferably depressed to form a recess for the bend of the bow 6 so that said bow is substantially flush with the side of the clip as best shown in Figs. 4 to 6.

15 In service the user inserts his fore finger into the finger opening 2 and passes the open jaws of the clip on opposite sides of the edge portion of the skin or other stock. The jaws are then closed upon the stock by throwing the actuating arm into closed position. When a sufficient number of the clips have been secured to the edge portion of the stock in the manner above described, the attaching spurs are inserted into the openings in the foraminated support, clips are then added where needed and the stock is stretched and secured upon the support for drying.

It will be apparent that a clip made in accordance with the invention as above described is strong, durable and adapted firmly to grip the stock and retain it against the severe stresses and strains incident to the drying of the skin. It will be equally clear that as the mount for the jaw actuating member is independent of the body of the clip it can be made of a different material or different grade of material from the remainder of the parts, and further there is no weakening of the material by bending or folding as in the older construction wherein ears or the like

are bent or folded up from the body of the clip to form a mount for the actuating member.

We claim:

1. A clip comprising relatively movable jaws, a jaw actuating member, an attaching spur and a mount for said actuating member loosely engaging the other elements of the clip. 45

2. A clip comprising relatively movable jaws having slots spaced inwardly from the edges thereof, a jaw actuating member, an attaching spur and a mount for said actuating member independent of the other elements of said clip and loosely disposed in said slots. 50

3. A clip comprising relatively movable jaws, each having a pair of slots spaced inwardly from the edges thereof, a jaw actuating member, an attaching spur, and a mount for said actuating member, comprising a U-shaped bow loosely disposed in said slots, the free ends of said bow projecting beyond one of said jaws and said actuating member pivoted to said free ends. 60

4. A clip comprising relatively movable jaws, each having a pair of slots spaced inwardly from the edges thereof, a jaw actuating member, an attaching spur, a mount for said actuating member comprising a U-shaped bow loosely disposed in said slots, the free ends of said bow projecting beyond one of said jaws and said actuating member pivoted to said free ends, and the bend of 70 said bow being substantially flush with the side of said clip. 75

Signed by us at Salem, Massachusetts, this 13th day of December, 1920.

ALVAH P. THOMPSON.
WILLIAM L. BAXTER.
